(57) **CLAIM**

The ornamental design for a monitoring camera as shown and described.

DESCRIPTION

FIG. 1 is a top, front, right perspective view of a monitoring camera showing my new design;

FIG. 2 is a front elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a rear elevational view thereof; and,

FIG. 8 is an enlarged detail view taken from area '8' in FIG. 7.

The evenly spaced broken lines represent portions of the monitoring camera in which the design is embodied that form no part of the claimed design. The dot-dash broken lines represent the extents of the detail views and form no part thereof. The dot-dot-dash broken lines in FIGS. 7 and 8 represent the boundary of the claimed design.
